UNITED STATES PATENT OFFICE.

ELIZABETH M. GILBRIDE, OF NORTH ATTLEBORO, MASSACHUSETTS, ASSIGNOR TO
CHARLES K. GROUSE COMPANY, A CORPORATION OF MASSACHUSETTS.

DESIGN FOR A SAFETY-PIN.

46,850.

Specification for Design.

Patented Jan. 12, 1915.

Application filed November 7, 1914. Serial No. 870,920. Term of patent 3½ years.

To all whom it may concern:

Be it known that I, ELIZABETH M. GILBRIDE, a citizen of the United States, residing at North Attleboro, in the county of Bristol and State of Massachusetts, have invented a certain new, original, and ornamental Design for a Safety-Pin, of which the following is a specification.

In the accompanying drawing which forms a part of this specification, the figure

is a front elevation of a safety pin embodying my new design.

I claim:—

The ornamental design for a safety pin, as shown.

ELIZABETH M. GILBRIDE.

Witnesses:

HAROLD W. MASON,
JOSEPH E. PFEIFFER.
